UNITED STATES PATENT OFFICE.

FREDERIC B. CAMORS AND CHARLES PELLETIER, OF NEW ORLEANS, LOUISIANA.

RAILWAY-SIGNAL.

No. 866,831:

Specification of Letters Patent.

Patented Sept. 17, 1907.

Application filed May 1, 1906. Serial No. 314,706.

To all whom it may concern:

Be it known that we, FREDERIC B. CAMORS and CHARLES PELLETIER, citizens of the United States and the République of France, respectively, residing at 5 New Orleans, in the parish of Orleans and State of Louisiana, have invented new and useful Improvements in Railway-Signals, of which the following is a specification.

Our invention pertains to railway signals of the 10 electric type, and consists in the peculiar and advantageous electric signal hereinafter described and claimed.

In the accompanying drawings, forming part of this specification: Figure 1 is a view illustrating diagrammatically a section of track, two cars on said section of track, and the car and track equipments of our improvements; the lower wire extending between the rails indicating that said rails are continuations of each other, and the next upper wire extending between the conductor bars indicating that said bars are continuations of each other. Fig. 2 is an enlarged view of an indicator or ohmmeter, one of which is included in the equipment of each car. Fig. 3 is a similar view of one of the commutators of the car equipments. Fig. 4 is a broken plan view of a section of track provided with the track portion of our improvements. Fig. 5 is a plan view of a siding switch equipped with our improvements; the said switch being shown as open—*i. e.*, in position to cause a train 30 to pass from the main track into the siding. Fig. 6 is a broken view illustrating one of the car equipments as carried by an ordinary locomotive. Fig. 7 is an enlarged, detail view of one of the devices through the medium of which the bell circuits are completed and 35 the bells caused to ring until the said circuits are broken by the engineers on the respective cars. Fig. 8 is a diagrammatic view of the semaphore mechanism comprised in our improvements. Fig. 9 is an enlarged detail view illustrating one commutator and 40 the electrical connections therefor. Fig. 10 is a detail section illustrating the commutator handle. Fig. 11 is a detail side elevation showing the commutator hook of one telephone and certain appurtenances thereof. Fig. 12 is a diagrammatic view of certain 45 telephone elements hereinafter referred to in detail. Fig. 13 is an enlarged cross-section of the block P^1 of the telephone.

Referring by letters and numerals to said drawings and more particularly to Figs. 1 to 7, thereof: m are 50 track rails comprised in the broken section of track shown in Fig. 4, and p is a conductor bar arranged between the rails m and insulators q , whereby it is insulated from the earth. The conductor bar p preferably extends continuously a distance of five miles, 55 and opposite the interruptions between the said bar

p and adjoining bars of the same kind, bars t , each of which is preferably about two miles long, are arranged. The said bars t are suitably insulated from the earth, and said bars t are only conductors at such times as they may be in contact with the brushes on 60 the cars. The said brushes being connected electrically will make these bars t alive during the passage of the train only; there being three brushes on each car in order to make the contacts regardless of the direction the train may be traveling in. The conductor p 65 not being continuous, the bars t merely serve to establish electric communication between the two sections of conductor p by means of the contact brushes on the cars.

In Fig. 1, the lower wire m' indicates that the rails between which it extends are continuous rails of a single track, and the next upper wire p' indicates that the conductor bars p between which it extends are parts of a continuous bar in the longitudinal center of the 70 said single track.

Two car equipments A are shown in Fig. 1. These car equipments are similar in construction, and therefore a detailed description of the equipment shown at the left of Fig. 1 will suffice to impart a definite understanding of both. The said equipment comprises a 80 case a , an indicator or ohmmeter b for informing the engineer regarding the proximity and the distance in miles in front or in rear of another train on the same section of track, an electric bell c , a device d for completing the circuit of the bell c , a volt-meter e for testing the condition of the sources of electric energy, presently described, a peculiar commutator f , a source of electric energy g , preferably a set of galvanic batteries; a source of electric energy h , preferably a set of galvanic batteries, a source of electric energy h' , preferably a 90 single galvanic battery, three brushes r electrically connected together, a conductor l leading to the conductive frame carrying the brushes r , a brush r' , Fig. 6, bearing against an axle of the car and serving in combination with said axle and the wheels thereon to form 95 a conductor l , shown diagrammatically in Fig. 1, designed to lead current to the rails m , a peculiar current-reverser k designed to be operated from the axle of the car and arranged to change the direction of the current at intervals, say every quarter of a mile, and 100 a telephone P designed to enable the engineer to converse with the engineer of another car on the same conductor section. In the current reverser k two conductive sections z^4 , preferably of brass, are electrically connected by a conductor z^4 , and between said sections 105 z^4 , sections of insulating material z^5 are arranged. These parts are all carried by a drum, and to the drum are opposed four equi-distant brushes z^6 as shown. When two opposite brushes z^6 are presented to the insulating sections z^5 , there will of course be no current 110

passing between the said brushes, but when the drum is turned through a quarter of a revolution, a passage for the current will be established between the mentioned brushes for the current.

- 5 The indicator or ohmmeter *b* comprises a box *b*² for excluding dust and moisture, a dial *b*² divided into two parts for use in indicating the distance in miles between two points of danger on the track, an armature *b*³, a coil *b*⁴ whose resistance is calculated for the length 10 of the section, and a pointer *b*⁵ of proper weight. The said pointer *b*⁵ is designed to extend to the left or the right to indicate the position of the car, relative to another car. The electric bell *c* is preferably of the conventional type and need not, therefore, be described 15 in detail. The device *d* for completing the circuit of the bell *c* is, however, of the peculiar construction shown in Fig. 7—that is, it comprises a dust and water-proof case *d*¹, a conductive support *d*² therein, electro-magnets *d*² arranged on the support *d*² and having coils 20 of great resistance electrically connected together, wires 1 in circuit with the coils of the magnets *d*², a conductive support *d*³, an armature *d*³ connected to the support *d*², a tactile spring *d*⁴ for pulling the armature *d*³ back when the magnets *d*² are deenergized, and a spring 25 catch *d*⁵ having a beveled head *d*¹⁰ designed to engage the armature *d*³ and hold the same against the magnets *d*², and also having a handle *d*⁶ extending outside the case and designed to enable the engineer to readily draw the catch out of engagement with armature *d*³ to permit 30 the latter to move away from the magnets and thereby break the bell circuit.
- It will be noticed by reference to Figs. 1 and 7, that when the magnets *d*² are energized by current passing through the wires 1, the armature *d*³ will be attracted 35 to the magnets *d*² and will be held there-against by the head *d*¹⁰ on catch *d*⁵. Because of this, the circuit in which the bell *c* is arranged will be completed, and hence current will pass from the positive pole of the source of electric energy *h* through the wire 2 between 40 the said pole and bell *c*, the wire 2 between said bell *c* and the conductive support *d*², Fig. 7, the cores of the electro-magnets *d*², the armature *d*³, the conductive support *d*², and the wire 2 between said support *d*² and the negative pole of the said source of energy *h*. In 45 consequence of this the bell *c* will be caused to ring with a view of attracting the notice of the engineer, until the engineer through the medium of the handle *d*⁶ disengages catch *d*⁵ from the armature *d*³ when the spring *d*⁴ will pull the said armature *d*³ away from the 50 magnets *d*² and the bell circuit will be broken and the bell silenced. The commutator *f*, Figs. 1, 3, 9 and 10, comprises seven contact pieces *f*¹, two of which are connected through wires 6 and 7, respectively, Figs. 1 and 9, with the positive pole of the set of batteries *g* and the 55 positive pole of the set of batteries *h*, a piece *f*⁷ taking alternately the positive of the sets of batteries *g* and *h* through certain of the contact pieces *f*¹ and connected through a wire 1, Figs. 1 and 9, with the positive of the volt-meter *e*, and an insulated arm *f*⁸ having at its extremity a piece of copper *f*⁹ used in connecting two contact pieces *f*¹, as shown in Fig. 9. Three of the contact pieces *f*¹ are electrically connected together, and are also connected through wire 5 with the negative of the volt-meter *e*. With the commutator arranged 60 as shown in Fig. 9 for the control of the batteries in set 65

h, the current from the positive pole of the said set *h*, passes through wire 7, one contact piece *f*¹, the piece of copper *f*⁹, then through wire 1 to the positive of the volt-meter *e*, then through said volt-meter, then back through the wire 5 to one of the electrically connected contact pieces *f*¹, then through the said connected contact pieces *f*¹, the contact part *f*⁹, the contact piece *f*¹ at the left thereof and through wire 4 to the negative pole of the set of batteries *h*. When the parts *f*⁷ and *f*⁸ are placed in a position opposite to that shown in Fig. 9, 75 the same results are obtained for the control of the batteries in set *g*.

The electrical connections illustrated are such that when two cars equipped with our improvements are on the same conductor *p*, the electric current passes 80 from the positive pole of the set of batteries *g* in the equipment at the left of Fig. 1 through the wire 1 to and through the current reverser *k* of said equipment, then through the wire 1 to the telephone *l*, of said equipment, past the brushes of the said telephone at 85 *l*¹, then through the conductor 1 of the equipment to the rails *m*, then from the rails through the conductor 1 to the telephone *l*¹ of the equipment at the right of Fig. 1, then past the brushes of said telephone at *l*¹, then through the wire 1 of said equipment to and 90 through the current reverser *k* of said equipment, then through the wire 1 of the equipment to and through the ohmmeter *b* thereof, then through the wire 1 to and through the coils of the magnets *d*² in the device *d* of said equipment, then through the wire 1 to the telephone *l*¹ of the said equipment, past the brushes of the said telephone at *l*¹⁰, then through the conductor 1 of said equipment to the brush frame and the middle brush *r* thereof, then through the conductor *p*, then through the middle brush *r* and the brush hanger of 100 the equipment at the left of Fig. 1, then through the conductor 1 of the latter equipment to the telephone *l* thereof, then past the brushes of the said telephone, as indicated by *l*¹, then through the wire 1 of said equipment to and through the coils of the electro-magnets *d*² in the device *d* thereof, then through the wire 1 to and through the ohmmeter *b* of said equipment, and then through the wire 1 to the negative pole of the set of batteries *g* of said equipment. 105 Because of the electric current taking the course just 110 described from the positive pole of the set of batteries *g* in the equipment at the left of Fig. 1 back to the negative pole of the said set of batteries *g*, the electro-magnets *d*² in the devices *d* of both equipments are energized, and the bells *c* of both equipments are set ringing because of the completion of the independent bell circuits—*i. e.*, the circuits each of which includes a bell *c*, a set of batteries *h*, and wires 2. It will also be noticed that the bells *c* will continue to ring with a view of putting the engineers on notice until the engineers 115 120 by pulling downward on the handles *d*⁶ of devices *d* release the armatures *d*³ from the catches *d*⁵ of said devices to permit of movement of the armatures under the action of the springs *d*⁴ in a direction away from the electro-magnets *d*². It will be further noticed that on 125 the completion of the circuit including the two equipments, the wires 1, the rails *m* and the conductors *p*, the pointers of the two ohmmeters will indicate the distance the two equipments or cars are apart, and the ohmmeter pointer of each equipment or car will indi- 130

cate the relative location of the other equipment or car—*i. e.*, whether it is behind or in front of its respective car. At this point we deem it well to state that the engineers ordinarily will not release the armatures 5 d^3 from the catches d^4 until after the described circuit from the positive pole of the set of batteries g of the equipment at the left of Fig. 1 back to the negative pole of the said set of batteries g is broken by the removal of the telephone receivers and transmitters from 10 the commutator hooks of the telephones in the manner which will now be described in detail.

In Fig. 11, the telephone brushes l^8 and l^{10} of the equipment at the left of Fig. 1, and the telephone commutator-hook B of said equipment are shown in their 15 normal positions—*i. e.*, the positions they occupy when the body B' carrying the telephone receiver C and transmitter D is hung on the hook B, and consequently the two brushes l^8 are together or in contact as are also the two brushes l^{10} to complete the circuit described 20 from the positive pole of the batteries g in the equipment at the left of Fig. 1 back to the negative pole of said batteries. When, however, the body B' of the telephone is removed from the hook B, and the inner arm of the said hook gravitates or swings downward, the 25 wedge-like block l^4 , Fig. 13, carried by the hook will move down between and thereby separate the brushes l^8 , and the similar block l^5 also carried by the hook will assume a position between and separate the brushes l^{10} , all as clearly shown in the diagrammatic view Fig. 30 12. The said blocks l^4 and l^5 respectively comprise a section of conductive material and a section of insulating material, and hence it follows that when the blocks are in the position shown in Fig. 12, one brush l^8 will be electrically separated from the other, and the 35 brushes l^{10} will also be electrically separated. On the replacing of the body B' on the hook B, the blocks l^4 and l^5 will be carried from between the brushes l^8 l^8 and l^{10} l^{10} , respectively, when the brushes l^8 will spring together as will also the brushes l^{10} . In Fig. 12, the 40 brushes l^8 and the brushes l^{10} of one equipment are shown electrically separated; and when the brushes l^{10} of the other equipment are similarly separated it will be seen that the telephones of the two equipments will be connected through the rail m and the conductor p so as 45 to enable the engineers on the two trains to converse with a view of imparting detailed information each to the other. In this connection it will be noticed that the positive and negative poles of the battery b of each equipment are electrically connected with the telephone 50 thereof through wires 3 in the manner well known in the telephone art and which need not, therefore, be described in detail.

At crossings and other necessary points where there is travel across the track we contemplate dispensing 55 with the upper conductors p and t and electrically connecting the portions of said conductors p and t at opposite sides of the crossing by wires or other suitable means extending below the surface of the crossing.

u , Fig. 5, is a box located at one side of the track adjacent to a siding switch and containing a stationary contact piece E and a movable contact piece E' .

v is an electrical connection between the movable contact piece E' and the conductor p .

w and w' are movable switch rails or points; the 65 rail w being permanently connected in an electrical

manner to the adjacent main track rail m and electrically isolated from the other main track rail w' is an electrical connection between the stationary contact piece E and the switch rail w .

F is a rod connecting the switch rails w and w' so as 70 to cause the same to move together.

G is a switch-moving rod connected to the rod F, and H represents means through which the rod G is connected with but insulated from the movable contact piece E' . By virtue of this construction it will be 75 seen that when the rod G is moved to open the switch as shown in Fig. 5 it will move the contact piece E' against the contact piece E, while when said rod G is moved to close the switch and reestablish the main line, it will move the contact piece E' away from the 80 contact piece E. With the switch open and the contact pieces E E' together as shown in Fig. 5, the switch rail w is electrically connected with the conductor p , and hence when a car is on the section of conductor p in which the switch is arranged, the circuit from the 85 positive pole of the set of batteries g on the car to the negative pole of said set of batteries will be completed through the rail m , switch rail w , conductor w^2 , contact pieces E and E' , conductor v and conductor p , and hence the bell c in the car will be caused to ring, 90 and at the same time the pointer of the ohmmeter b will be caused to extend to one of the marks "S" so as to give notice to the engineer that a switch in the section is open, and inform him whether the open switch is in front or in rear of this car. 95

For the purpose of apprising the engineer of a train that the train is on a section of track where the semaphore is set against his train—*i. e.*, positioned to warn the engineer of danger, we provide the electromechanical means shown in Fig. 8. The said means comprises 100 a bell crank m^7 for working a semaphore n^7 , a rod p^7 connected to said bell crank and equipped with an arm q^7 , a stationary contact r^7 connected to a body of insulating material s^7 and electrically connected through a wire t^7 to the conductor p , a movable contact u^7 mounted on the insulating material s^7 and normally resting away from the contact piece r^7 and electrically connected through a wire v^7 with one of the track rails, a box or casing w^7 containing the contacts and the body of insulating material, a cylinder x^7 arranged in said box, a rod y^7 extending through the cylinder and connected to the movable contact u^7 and arranged to be pressed forward by the arm q^7 on rod p^7 , and a spring z^7 in the casing x^7 for moving the rod y^7 rearwardly and normally holding the contact u^7 away 110 from the contact r^7 as shown by dotted lines. It will be understood from the foregoing that when the rod p^7 is moved forward to move the semaphore to the danger position illustrated, the contact u^7 will engage the contact r^7 as shown by full lines with the result that 115 the insulated conductor p is placed in closed circuit with the rails by the wires t^7 and v^7 . From this it follows that when a car provided with our novel equipment arrives in the section in which the semaphore is located, the bell c and the ohmmeter b of said equipment 120 will be actuated to notify the engineer that the semaphore is set against him. When the semaphore is set for a clear main track, the contact u^7 obviously rests away from the contact r^7 and hence no notice is given 125 to the engineer. 130

The construction herein shown and described constitutes the preferred embodiment of our invention, but it is obvious that in practice various changes in the form, construction and relative arrangement of parts may be made without involving departure from the scope of our invention as defined in the claims appended.

Having described our invention, what we claim and desire to secure by Letters-Patent, is:

10. 1. A railway signal apparatus of the electric type, comprising a section of track, a conductor insulated from the earth, a car movable on the track, means carried by the car for making electrical contact with one of the rails of the track, means carried by the car for making electric contact with the said conductor, an electrical signal carried by the car, a source of electric energy also carried by the car and arranged in a normally open circuit with the electric signal, an electro-mechanical device carried by the car for closing the said circuit and actuating the electric signal, the said electro-mechanical device being arranged in a normally interrupted signaling circuit with a source of electric energy, a telephone, one of the track rails and the conductor, and the said telephone carried by the car and arranged in a third circuit with a source of electric energy also carried by the track rail and the conductor and having a commutator hook and means whereby the signaling circuit is unaffected when the commutator hook is in one position and is interrupted when said hook is in another position, and the third or telephone circuit is uninterrupted when the commutator hook is in the last mentioned position and is interrupted when said hook is in the first mentioned position. 50
15. 2. A railway signal apparatus of the electric type, comprising a section of track, conductor sections separated from each other and insulated from the earth, a conductor extending in the same direction as the first mentioned conductors and arranged opposite the space between the same and insulated from the earth, a car movable on the track, means carried by the car for making electrical contact with one of the rails of the track, brushes carried by the car and arranged side by side to engage the said conductor sections and conductor and electrically connected together, a current reverser carried by the car and arranged to derive motion from one of the wheels thereof, an electrical signal carried by the car, a source of electric energy also carried by the car and arranged in a normally open circuit with the electric signal, an ohmmeter carried 55
20. by the car, an electro-mechanical device carried by the car for closing the said circuit and actuating the electric signal; the said electro-mechanical device being arranged in a normally interrupted signaling circuit with a source of electric energy, the current reverser, the ohmmeter, a telephone, one of the track rails and the brushes, and the said telephone carried by the car and arranged in a third circuit with a source of electric energy, the track rail and the brushes and having a commutator hook and means whereby the signaling circuit is unaffected when the commutator hook is in one position and is interrupted when said hook is in another position, and the third or telephone circuit is uninterrupted when the commutator hook is in the last mentioned position and is interrupted when said hook is in the first mentioned position. 60
25. 3. A railway signal apparatus of the electric type, comprising a section of track, conductor sections separated from each other and insulated from the earth, a conductor extending in the same direction as the first mentioned conductors and arranged opposite the space between the same and insulated from the earth, a car movable on the track, means carried by the car for making electrical contact with one of the rails of the track, brushes carried by the car and arranged side by side to engage the said conductor sections and conductor and electrically connected 65
30. together, a current reverser carried by the car and arranged to derive motion from one of the wheels thereof, an electrical signal carried by the car, a source of electric energy also carried by the car and arranged in a normally open circuit with the electric signal, an ohmmeter carried 70
35. by the car, an electro-mechanical device carried by the car for closing the said circuit and actuating the electric signal; the said electro-mechanical device being arranged in a normally interrupted signaling circuit with a source of electric energy, the current reverser, the ohmmeter, a telephone, one of the track rails and the brushes, and the said telephone carried by the car and arranged in a third circuit with a source of electric energy, the track rail and the brushes and having a commutator hook and means whereby the signaling circuit is unaffected when the commutator hook is in one position and is interrupted when said hook is in another position, and the third or telephone circuit is uninterrupted when the commutator hook is in the last mentioned position and is interrupted when said hook is in the first mentioned position. 75
40. In testimony whereof we have hereunto set our hands in presence of two subscribing witnesses. 80
